UNITED STATES PATENT OFFICE.

ROBERT A. GILLESPIE, OF ALLEGHENY, PENNSYLVANIA, ASSIGNOR TO
GILLESPIE MANUFACTURING COMPANY, OF PITTSBURG, PENNSYLVANIA.

TUBE-COUPLING.

SPECIFICATION forming part of Letters Patent No. 740,003, dated September 29, 1903.

Application filed December 24, 1902. Serial No. 136,440. (No model.)

To all whom it may concern:

Be it known that I, ROBERT A. GILLESPIE, a citizen of the United States, residing at Allegheny, in the county of Allegheny and State of Pennsylvania, have invented certain new and useful Improvements in Tube-Couplings, of which the following is a specification, reference being had therein to the accompanying drawings.

10 This invention relates to couplings for the joints of smooth-end tubing or pipes, and has particular reference to the formation of the surfaces of the coupling members between which the gaskets or packing-rings are confined, also to the shape of the gaskets, whereby the couplings are effectively and permanently sealed.

15 In the accompanying drawings, Figure 1 is a longitudinal sectional view of a coupling embodying my invention. Fig. 2 is a similar view of the coupling with the parts detached. Fig. 3 is a face view of one of the coupling-rings. Figs. 4 and 5 are detail sectional views enlarged.

20 Referring to the drawings, 2 designates the coupling-sleeve, which receives the ends of pipe-sections 3. 4 represents the rubber packing rings or gaskets, 5 the coupling-rings, and 6 the bolts which connect and draw up the 25 coupling-rings, the bolts extending through the apertured ring-ears 7 in the usual manner. The end surfaces of sleeve 2 form abutments for the packing-rings and are each doubly beveled at 8 and 9, forming annular 30 ridge 10, outer bevel 8 being preferably more gradual than bevel 9—say at an angle of thirty degrees to the plane of sleeve-axis—and bevel 9 at a sharper angle of about forty-five degrees. However, I do not confine myself 35 in this regard.

The inner face of each packing-ring 4 is doubly beveled at 11 and 12 complementary with the sleeve double bevel 8 and 9, while the opposite face thereof is beveled outwardly 40 or backwardly at 13 and grooved at 14 to receive annular bead 15 on the inner countersunk end face of coupling-ring 5. The inner side of ring 5 is preferably formed with a double bevel divided by bead 15, constituting 45 the distinct packing-compressing faces 16

and 17, with outer face 16 in advance of face 17.

The annular rim or edge 18 of the coupling-ring forms a pocket for the gasket, and when drawn up, as in Fig. 1, said rim overlaps sleeve 2 and completely incloses the packing and preserves the same against injury, wear, and deterioration incident to exposure.

When drawing up the coupling-rings in applying the coupling, outer face 16 of each 60 coupling-ring being in advance of inner face 17 the outer portion of the gasket is subjected to greater pressure than the inner portion, also is compressed slightly in advance of the latter, with the result that the looser inner 65 portion is crowded or wedged tightly against the pipe before the maximum pressure is attained. At the inner face of the gasket bevel 8 serves to crowd or wedge the rubber laterally against the pipe and inward against the 70 inner sharper bevel 9, ridge 10 tending to hold or confine the rubber as thus compressed.

In couplings of this character the packing-rings should tightly impinge the tubing in order that an efficient and permanent seal 75 may be had. With my improvements the whole tendency of the beveled sleeve ends and coupling-rings is to crowd or wedge the whole of the packing-rings against the pipe in addition to compressing the same longitudinally. 80

I claim—

1. In a tube-coupling, a packing-abutment, a packing-ring, and a coupling-ring having its packing-engaging surface in distinct parallel faces—one in advance of the other—and each 85 of frusto-conical form.

2. In a tube-coupling, a packing-abutment, a packing-ring, a coupling-ring having an inwardly-receding packing-engaging surface parallel with the surface of the packing-ring 90 it engages and corresponding in width to the width of the packing-ring and adapted to compress the entire section thereof, said packing-engaging surface having distinct annular faces one in advance of the other. 95

3. In a tube-coupling, a packing-compressing ring having its packing-engaging surface formed with distinct parallel faces.

4. In a tube-coupling, a packing-compressing ring having its packing-engaging surface 100

formed with distinct parallel inwardly-receding faces.

5. In a tube-coupling, a packing-compressing ring having its packing-engaging surface formed with distinct faces and a bead intermediate and separating the faces.

6. In a tube-coupling, a packing-abutment, packing, and a compressing-ring having its packing-engaging side formed with parallel faces oblique to the ring-axis.

7. In a tube-coupling, a packing-abutment, packing, and a compressing-ring having an annular projection on its inner side dividing said side into two faces disposed toward the abutment and adapted to force the packing thereagainst, one face being in advance of the other.

8. In a tube-coupling, a packing-abutment, packing, and a coupling-ring having distinct packing-engaging faces, a bead intermediate the faces, the face of greater diameter being nearest the abutment or in advance of the other face.

9. In a tube-coupling, a packing-abutment, a packing-ring having an end face oblique to the ring-axis and formed with an annular groove, the portion of the face of greatest diameter being nearest the abutment, a coupling-ring having distinct packing-engaging faces with the face of greater diameter in advance of the face of lesser diameter, and an annular projection on the coupling-ring intermediate said faces.

10. In a tube-coupling, a packing-abutment

having two faces disposed at an angle to each other with a ridge at the juncture of the faces, a packing-ring beveled to fit said abutment, and a coupling-ring having distinct packing-engaging faces with the face of greater diameter in advance of the other face.

11. In a tube-coupling, the combination of a tube-receiving sleeve having an inwardly-receding beveled end, the bevel being formed with distinct annular faces disposed at different angles to the sleeve-axis, packing, and means for forcing the packing against the beveled sleeve end.

12. In a tube-coupling, the combination of a tube-receiving sleeve having the inwardly-receding beveled ends, each bevel being formed with distinct annular faces disposed at different angles to the sleeve-axis, packing-rings, coupling-rings for forcing the packing-rings against the sleeve ends, and means for drawing the coupling-rings toward the sleeve.

13. As a new article of manufacture, a packing-ring having its outer side beveled to form a ring of tapering section, the bevel extending from the thickest portion of the ring to one edge thereof and formed with distinct faces of frusto-conical form, said faces being oblique to each other and to the ring-axis.

In testimony whereof I affix my signature in presence of two witnesses.

ROBERT A. GILLESPIE.
